UNITED STATES PATENT OFFICE.

JOHN W. PITTS, OF BISBEE, ARIZONA, ASSIGNOR TO PITTS ROYALTY COMPANY, OF BISBEE, ARIZONA, A CORPORATION OF ARIZONA.

MECHANICAL MOVEMENT.

1,056,746.

Specification of Letters Patent. Patented Mar. 18, 1913.

Original application filed March 1, 1911, Serial No. 611,551. Divided and this application filed May 15, 1911. Serial No. 627,099.

To all whom it may concern:

Be it known that I, JOHN W. PITTS, a citizen of the United States, and a resident of Bisbee, in the county of Cochise and State of Arizona, have made certain new and useful Improvements in Mechanical Movements, of which the following is a specification.

My invention relates to improvements in mechanical movements, and it consists in the combinations, constructions, and arrangements herein described and claimed.

An object of my invention is to provide a device whereby a reciprocatory motion may be converted into a rotary motion or vice versa.

A further object of my invention is to provide a mechanical movement of the kind specified in which there is less loss of power in the conversion of one motion into the other and in the ordinary mechanical movements.

Other objects and advantages will appear in the following specification and the novel features of the device will be particularly pointed out in the appended claims.

My invention is illustrated in the accompanying drawings forming part of this application in which—

Figure 1 is a perspective view of the mechanical movement, Fig. 2 is a side view of the eccentric, Fig. 3 is a section through the eccentric on the line 3—3 of Fig. 2, Figs. 4, 4^a, 4^b, and 4^c are diagrammatic views showing the relative positions of the eccentric when a mechanical movement is connected with the piston of a reciprocating engine, Fig. 5 is a side view of a modified form of eccentric, Fig. 6 is a section along the line 6—6 of Fig. 5, Fig. 7 is a diagrammatic view showing the employment of the modified form of the mechanical movement shown in Figs. 5 and 6 with a plurality of engines, Fig. 8 is a detail sectional view showing another modification of the mechanical movement, Fig. 9 is a side view of the mechanism shown in Fig. 8, Fig. 10 is a detail view showing a further modified form, and Fig. 11 is a sectional view along the line 11—11 of Fig. 10, looking in the direction of the arrow.

The mechanism disclosed in the present application has been set forth in a prior application, Serial Number 611,551, filed

March 1, 1911. The present case is a divisional application.

The mechanism which forms the subject of this invention is best illustrated in its entirety in Fig. 1. Before taking up the assemblage of the parts, however, I will explain the construction of the elements which when combined comprise the movement. Referring now particularly to Figs. 2 and 3, it will be seen that I have provided a body portion 1 having a cylindrical opening 2 therethrough. This body portion terminates at each end in a gear, one of these gears being shown at 3 and the other at 4. The body portion 1 has an integral arc-shaped portion 5 having side flanges 6 for a purpose herein-after explained. It will be observed that the center of the arc-shaped portion is at the point 7, which is on a common tangent with the gears 3 and 4. Arranged to mesh with the gears 3 and 4 are the internal gears 8 and 9 respectively. Both of the gears 8 and 9 are designed to be held in a stationary position. In Fig. 1 I have shown a portion of an engine frame 10 having a bolt arranged to pass into the tongue 9^a of the gear 9, merely to illustrate the fact that the gear 9 is stationary, and not movable. It will be understood that similar means or any suitable means may be applied to the gears 8 or 9 for the purpose of holding them in stationary positions. The gear 3, as stated, meshes with the internal gear 8 and the gear 4 is designed to mesh with the internal gear 9. The shaft 11 extends through the opening 2 and the gears 3 and 4 are therefore loosely mounted on the shaft. The end of this shaft 11 at one end is fastened by means of a key 12 to a crank member 13 (see Fig. 1). This crank member is enlarged at the opposite end to form an arc-shaped counterweight 14. A shaft 15 having a reduced portion 16 has its end secured to the crank member, as shown in Fig. 1. A similar arrangement is provided for the shaft 17, this shaft being secured to the crank member 13^a similar to the crank member 13 and being provided with a counterweight 18 similar to the counterweight 14. A counterweight 19 is attached to one side of the gear 4 between the gears 8 and 9 adjacent the gear 9, while a similar weight 20, shown in dotted lines, is attached to one side of the gear 3 adjacent the stationary gear 8.

Arranged to encircle the arc-shaped member 5 is a strap 21 which is held together at its top by means of a bolt 22. This strap fits in between the flanges 6 and the strap 5 and the arc-shaped member 5 having a movement relative to one another. The strap 21 is rigidly attached to the piston rod P on one side and P' on the other. In Fig. 1, I have shown two piston rods on each side, 10 one piston rod P and a smaller piston rod p on one side and the piston rods P' and p' on the other side. These rods are rigidly attached to the strap as stated, and as far as the mechanical movement is concerned 15 might be a single rod instead of two.

From the foregoing description of the various parts of the device the operation thereof may be readily understood. Consider the diagrammatic illustration in Fig. 4. In this 20 figure the piston rod P is connected to a piston P^x in a cylinder C. The piston rod P is connected with the strap 21 on the member 5. Since the gears 3 and 4 operate precisely in the same manner it is sufficient to 25 show the action of one of these gears. Thus in Fig. 4, the gear 3 is in mesh with a stationary internal gear 8. A movement of the piston P^x into the position shown in Fig. 4 will cause the gear 3 to revolve in the direction shown by the small arrow, while 30 the center of the gear, i. e., the center of the shaft 11 will revolve in the opposite direction as shown by the large arrow. In other words, where the gear 8 is stationary the 35 movement of the small gear 3 around on the interior of the gear 8 will cause the shaft 11 to revolve about the center of the large internal gear 8, and will hence cause the revolution of the shafts 15 and 17. In 40 Fig. 4 I have shown different positions of the piston P^x and of the strap 21. It will be seen that the strap is moved on a line parallel with the piston rod, while the gear 38 is traveling around the interior of the 45 stationary gear 8, and thereby causing the rotation of the crank shafts 15 and 17.

The peculiar mechanical movement by which the reciprocatory movement of a piston rod is changed into rotary movement 50 enables me to make use of a number of engines the combined force of which may be used to cause rotary movement without any danger of the engines working against one another. In Figs. 5 and 6, I have shown a 55 device by which any number of engines, from one to four, such as those shown in Fig. 7, may be coupled up together. In Fig. 5, it will be seen that there are two members similar to 5, i. e., 5^x and 5^y which 60 are provided at 180° apart. Obviously two such straps as 21 should be provided. In Fig. 7 there are four cylinders A, B, A' and B'. The piston of the cylinder A is at the 65 rear end of its stroke, and its strap 21 is therefore as near the cylinder A as it can

be. The piston of the cylinder B is also attached to the strap 21 and the center of the strap, which, as stated, is at the rear of the gear 3, moves on a straight line between the two pistons parallel to their axes. Now any other point on the circumference of the gear 3 will move back and forth in a straight line across the circle formed by the internal gear 8. The point 7^x on the opposite side of the gear 3 from the point 7 will move in 70 a straight line at right angles to the path of the point 7, and if this point 7^x be made the center of another arc-shaped member 5^y then a strap attached to the member 5^y may be operated by the pistons in the cylinders A' 75 and B' to aid in turning a common crank shaft 15^x. It will be seen that any number of cylinders may be used by providing extra straps and arc-shaped supports therefor which are attached to and integral with the 80 gears 3 and 4.

In Figs. 8 and 9, I have shown a modified form of mechanical movement in which the power may be applied either at the reciprocating end or at the rotating end. In these 90 figures M^t and M^s represent a pair of internal gears similar to the gears 8 and 9 already described. These gears like the gears 8 and 9 are designed to be held stationary. The teeth of the gears are arranged to mesh with 95 the teeth of the traveling gears F^s and F^t, a side view of the latter being shown in Fig. 9. The gear F^s is pivotally mounted on a crank shaft H^s upon which is also pivotally mounted a heavy wheel G^s. The companion traveling gear F^t is likewise mounted on a crank shaft H^t, and has a weighted 100 wheel G^t which is also pivotally mounted on the shaft. The weighted wheels G^s and G^t are joined by means of a shaft N^t and 105 the parts G^s N^t and G^t form a crank member for the connecting rods U^s and U^t. In this case, as in the case of the mechanical movement shown in Fig. 1, already described, when power is applied through the crank 110 shafts H^s and H^t, the gears will be caused to travel around on the inner side of the internal gear, but the shaft M^t will move directly across from one side of the internal gear to the other on a diametrical line, thereby causing the reciprocation of the rods U^s and U^t. The latter may be attached to any 115 machine such as a pump (not shown) so as to drive it. The power may be applied to the rods U^s and U^t, as for instance by means 120 of a wind mill (not shown) or by oppositely disposed engines such as that shown in Fig. 7. In the latter case, the cranks H^s and H^t will then be caused to revolve.

In Figs. 10 and 11 I have shown a still 125 further modified form in which the reciprocating rods are connected at two different points. An inspection of Figs. 10 and 11 will show that the arrangement of the parts is mainly the same except that the shaft N^t 130

is connected with a similar shaft N^s by means of a bar Z . Instead of having only one set of reciprocating rods there are two sets, to wit: U^s-U^t and U^v-U^w . The effect of this combination is to give a reciprocating movement to each of the rods when moved at right angles to each other. Thus the rods U^s-U^t move in a horizontal plane, while the rods U^v-U^w move in a vertical plane, the power being applied through the cranks H^s and H^t .

I claim:

1. In a mechanical movement, a crank shaft having a U-shaped central portion, a traveling gear pivotally mounted on said central portion of the crank shaft, a circular member integral with said gear and eccentric with respect thereto, a circular strap member carried by said eccentric member and having a rotary movement relative thereto, and a stationary internal gear arranged to be engaged by said traveling gear.

2. In a mechanical movement, a crank shaft having a U-shaped central portion, a weight carried by the crank shaft on the opposite side thereof from the U-shaped central portion, a traveling gear pivotally mounted on said central portion of the crank shaft, a circular member integral with said gear and eccentric with respect thereto, a circular strap member carried by said eccentric member and having a rotary movement relative thereto, and a stationary internal gear arranged to be engaged by said traveling gear.

3. In a mechanical movement, a pair of stationary internal gears, a crank shaft disposed centrally of said internal gears, a pair of integral traveling gears rotatably mounted on the center of said crank shaft and adapted to engage their respective internal gears, an integral circular member disposed between said traveling gears and being provided with side flanges, and a circular strap carried by said circular member between said side flanges and having a relative movement in respect to said circular member.

4. In a mechanical movement, a crank shaft, a grooved eccentric mounted for rotation on said crank shaft, a pair of gears mounted on said crank shaft and being connected with said eccentric, a pair of stationary internal gears arranged to mesh with the first mentioned gears, a circular strap member disposed in the groove in said eccentric, and piston rods for reciprocating said circular strap.

5. In a mechanical movement, a crank shaft having a U-shaped central portion, a traveling gear pivotally mounted on said central portion of the crank shaft, a circular member integral with said gear and ec-

centric with respect thereto, said circular member having peripheral side flanges, a circular strap member carried by said eccentric member between said side flanges and having a rotary movement relative to said eccentric member, and a stationary internal gear arranged to mesh with said traveling gear, disposed within the U-shaped portion of said crank shaft.

6. In a mechanical movement, a crank shaft having a U-shaped central portion, a pair of traveling gears rigidly connected together and pivotally mounted on the central portion of said crank shaft, a circular member integral with said gears and disposed between them, said circular member being eccentric of said gears, a circular strap member carried by said eccentric member and having a rotary movement relative thereto, and a stationary individual internal gear for each of said traveling gears disposed within the U-shaped portion of said crank shaft.

7. In a mechanical movement, a crank shaft having a U-shaped central portion, a pair of traveling gears rigidly connected together and pivotally mounted on the central portion of said crank shaft, a circular member integral with said gears and disposed between them, said circular member being eccentric of said gears, a circular strap member carried by said eccentric member and having a rotary movement relative thereto, a stationary individual internal gear for each of said traveling gears disposed within the U-shaped portion of said crank shaft, and counterweights secured to said crank shaft on the opposite side from said central portion.

8. In a mechanical movement, a crank shaft having a U-shaped central portion, a pair of traveling gears rigidly connected together and pivotally mounted on the central portion of said crank shaft, a circular member integral with said gears and disposed between them, said circular member being eccentric of said gears, a circular strap member carried by said eccentric member and having a rotary movement relative thereto, a stationary individual internal gear for each of said traveling gears disposed within the U-shaped portion of said crank shaft, counterweights secured to said crank shaft on the opposite side from said central portion on the outside of said stationary internal gears, and a piston rod rigidly connected with said circular strap member.

JOHN W. PITTS.
